UNITED STATES PATENT OFFICE.

JOHN CLULEE, OF WALLINGFORD, CONNECTICUT, ASSIGNOR TO THE INTERNATIONAL SILVER CO., OF MERIDEN, CONNECTICUT, A CORPORATION OF NEW JERSEY.

DESIGN FOR A HANDLE FOR SPOONS, FORKS, OR SIMILAR ARTICLES.

SPECIFICATION forming part of Design No. 36,284, dated April 14, 1903.

Application filed March 13, 1903. Serial No. 147,678. Term of patent 7 years.

To all whom it may concern:

Be it known that I, JOHN CLULEE, of Wallingford, in the county of New Haven and State of Connecticut, have invented and produced a new, original, and ornamental Design for a Handle for a Spoon, Fork, or Similar Article; and I do hereby declare the following, when taken in connection with the accompanying drawing and the letters of reference marked thereon, to be a full, clear, and exact description of the same, and which said drawing constitutes part of this specification and represents a face view of a handle for a spoon, fork, or similar article embodying my design.

This invention relates to an ornamental design for a handle for a spoon, fork, or similar article; and it consists in the configuration and ornamentation, as herein shown and described.

At the tip of the handle is a full-blown lily A, turned downward, a portion of the petals forming the outline of the tip of the handle, the extreme tip of which is formed by a scroll

F. Below the lily are buds G. At about the center of the handle is a second full-blown lily B, turned downward and its sides forming the outline of the handle, the lilies being connected by scrolls or stems C at opposite sides of the handle, which bow outward, forming a plain panel D. Below the lily B are interlaced stems E, forming an irregular outline to the stem, which in this portion is contracted.

Having fully described my invention, what I claim as new, and desire to secure by Letters Patent, is—

The ornamental design for a handle for a spoon, fork, or similar article, as herein shown and described.

In testimony whereof I have signed this specification in the presence of two subscribing witnesses.

JOHN CLULEE.
